UNITED STATES PATENT OFFICE.

CHARLES WHITNEY MORDEN, OF PORTLAND, OREGON.

FIXTURE FOR PACKAGES OF FOLDED PAPER OR OTHER MATERIAL.

1,219,366.

Specification of Letters Patent. Patented Mar. 13, 1917.

Application filed August 27, 1914. Serial No. 858,963.

To all whom it may concern:

Be it known that I, CHARLES W. MORDEN, a citizen of the United States, and a resident of the city of Portland, county of Multnomah, State of Oregon, have invented a certain new and useful Improvement in Fixtures for Packages of Folded Paper or Other Material, of which the following is a specification.

- 10 The object of my invention is to provide an inexpensive wall fixture serviceable for holding toilet paper, or paper towels, put up in package form, particularly a package made up from a reversely folded continuous strip divided into partly severed sheets, and made with apertures to permit it to be placed on the supporting member of my fixture. It is also my object, incidentally, to provide for an automatic forward feed of 15 the paper contained in the fixture by gravitation. My fixture is furthermore especially designed for holding the package of paper invented by me contemporaneously with this fixture.
- 20 The features of my invention are best understood by the description of the accompanying drawings:

Figure 1 is a front elevation of my fixture in its simplest form, and illustrates the practical use of my fixture;

Fig. 1^a is a detail of the wall bracket of this type of fixture.

Fig. 2 is a side elevation of my fixture related to the view thereof shown in Fig. 1;

35 Fig. 2^a is a detail of the back or gravity plate of my fixture, showing a section on the line x—x of Fig. 2.

Fig. 2^b is a detail of construction fully described in the body of the specification;

40 Fig. 3 is a front elevation of my fixture when constructed in the form of a case concealing within the package, but exposing the end of the outermost sheet;

Fig. 4 is a vertical section taken approximately on the line 4—4 of Fig. 3; in this view the paper package is shown in broken outline;

45 Fig. 5 is a plan view showing a detail of construction of a convenient type of lock for locking the case shut;

Fig. 6 is a fragmentary plan or top view of a strip of paper from which to form a package adapted for use in either of the described types of my fixture;

50 Fig. 6^a is a side elevation of such strip of paper;

Fig. 7 is a diagrammatic side elevation

illustrating the folding of the strip of paper in the process of forming a package adapted for use in that type of my fixture which includes downwardly inclined supporting members, for the purpose of feeding the paper forward by gravitation;

Fig. 8 shows how the strip, of which my package is formed, would be constructed in order to adapt the package to be supported from a wall fixture provided with only a single supporting member;

Figs. 9 and 10 show this type of package as supported by such fixture, Fig. 9 showing a front elevation and Fig. 10 a side elevation;

Fig. 11 shows a perspective front view of this type of fixture; and

Fig. 12 shows a diagrammatic top view of the package supported thereby.

I will describe the construction of the open or simple type of my fixture first. The wall bracket, a, is made of resilient wire rod and comprises a cross bar made with ears a' 80 for receiving screws a² for affixing to a wall.

The ends of the bracket are formed into parallel supporting members or arms b, b, preferably downwardly inclined so as to cause the paper mounted thereon to feed forward by gravitation; and the extremities of such arms are formed with in-bent portions c, c, constituting retaining means for the keeper g. The latter may also be made of wire, and the sides thereof are made with loops, as at h, h, so as to be adapted to be locked with said in-bent portions c, c, of the arms b, b, of the bracket. Back of the keeper g and slidably mounted on said arms of the bracket, a, is a back or gravity plate i. The latter is notched at its sides as at j, so that it may be mounted on the arms b of the bracket, to do which the arms are sprung apart. To prevent the gravity plate, i, from accidentally coming off the arms, b, it is made with lugs, 90 k (see Fig. 2^a) at its sides, in which lugs are inserted locking pins l. The gravity plate is not indispensable, but convenient. It may be substituted by a sheet of cardboard slidably mounted on said arms of the 95 wall bracket.

The in-bent extremities, c, c, of the arms b, b are so arranged as to be located over the unslotted portions connecting the sheets of the package; and the act of pulling the free 100 end m³ of the overlying sheet forward will sever said connecting portions.

In order to hold the keeper g firmly it may be made with an integral piece g', con-

ected by a tie wire f to the knuckle, e , formed at the lower end of a plate d , pendently supported on the cross-bar of the wall bracket a by its knuckle d' . Compare Figs. 5, 1^a and 2, 2^b. A screw d^2 holds the plate d rigid.

The paper package, n , to be used in my described type of fixture is made as illustrated in Figs. 6 and 7. It consists of a continuous strip of paper reversely creased at m^5 so as to form folds m^6 , m^7 , as illustrated in Fig. 7. The creases are alternately spaced farther apart and brought nearer together so that the folds will be stepped progressively and the package will assume a parallelogramic form conforming with the inclination given to the supporting arms b , b of the wall bracket a . When so arranged, the slits or perforations m^2 of the strip will (as graphically illustrated by the dash and dot line m^8 of Fig. 7) divide the package into a plurality of consecutive, folded sheets partially severed from each other, and alternately located at the top and bottom of the package.

The paper package is inserted by springing the arms, b , of the bracket, a , sufficiently apart so that their in-bent extremities, o , may pass through the slots m^4 at the sides 30 of the paper package.

If it is preferred to inclose the paper package in a case, then my fixture will be made as shown in Figs. 3 and 4.

The case, n , consists of a bottom, a front, 35 sides and an inclined top integrally formed. The case is hinged at n' to a wall plate o , secured to the wall by screws o' , as shown in Fig. 4.

At the sides of the wall plate, o , are provided perforated lugs t , in which are inserted the inner, bent portions of the arms u , u , made of resilient wire, the front ends of which arms are formed with inturned portions as at u' . The front n' of the case is the 45 equivalent of the keeper of my first described type of fixture. This keeper element n' has a space w cut out through which the end of the paper strip may be drawn, as represented by the dotted line m^3 in Fig. 4; and the keeper element n' has inwardly projecting, perforated integral portions n^3 , located in such cut-out part, through which the in-bent ends u' of the arms u are inserted, as shown in Fig. 3. The arms u are 55 downwardly inclined so as to cause the paper to feed forward by gravitation.

The top of the case, n , is locked to the top of the wall plate, o , by a locking device comprising an arrow-head lug o^2 and a locking member p consisting of a pair of resilient arms made of one piece of wire connecting a bow-like portion p^2 by which the locking member is secured on a stud q on the plate p^3 , which is riveted to the underside of the 65 top of the case by a rivet r . The resilient

arms p' grasp the arrow head of the lug o^2 , as shown in Fig. 5. The top of the case has a key-hole n^2 for inserting a key s , made with oppositely projecting webs, which, when the key is turned, spread the arms p' of the locking member apart, as shown in dotted lines in Fig. 5, and thus disengage said locking member from the lug o^2 .

The paper package used for this type of fixture is of the same construction as that used for the open type of my fixture.

A very simple type of my fixture, embodying the essential features of the other types of my fixture above described, is shown in Fig. 11. It consists of a wall plate 2, from which projects a hook 3. The latter is made with a shouldered head 4, exteriorly convexed so as to facilitate its insertion in the aperture of the package to be suspended from this fixture; the head 4 serving to keep the package from slipping off the hook 3. A wire rod 5 is rotatably inserted in the bore of the portions 6, 6 of the wall plate 2, and the ends of the rod 5 are formed into arms 7, 7, the extremities 8, 8 of which are bent inward and weighted pieces 9, 9 are thereon secured.

The paper package to be suspended from this type of fixture must be formed as illustrated in Fig. 8. 10 represents the strip, 11 the creases, and 12 the slits, these being made in similar manner as shown in Fig. 6 and above described. But the strip 10, instead of having notches cut in its sides, has cut-out apertures 13, located as shown in Fig. 8, and such apertures, when the strip is folded in the manner shown in Fig. 12, will be properly located for hanging the package 14 on the hook 3 of my fixture illustrated in Fig. 11. The pivoted rod 5 of the latter, and 105 its arms 7, 7, constitute the keeper operating to hold back the folds at the front of the package, but do not interfere with the tearing off of the sheets 15, 16 of the package, which tearing off is done by a side motion of 110 the hand. In placing the package 14 on its fixture, the keeper of the latter is lifted above the hook 3, the package is placed on the latter, and then the keeper is dropped against the face of the package. As sheets 115 are torn off of the package, the keeper will follow, and in so doing continue to perform its function.

The slots 17 at the sides of the strip 10 have no bearing on the invention; they 120 merely are provided in practice for facilitating the folding of the paper mechanically.

The inner face 4^a of the hook 4 is made with a knife-edge so as to facilitate the severing of the unperforated portion of paper 125 connecting consecutive sheets.

I claim:

1. A package supporting fixture of the character described comprising supporting means including a package supporting mem- 130

- ber, or members, a paper severing element provided at the extremity of the supporting member or members, such paper severing element alined approximately with the perforations partially severing the sheets of the package, and a keeper for restraining the outer folds or sections of the package.
2. A package supporting fixture of the character described comprising supporting means including laterally located supporting members, a paper severing element provided at the extremity of the supporting members, such paper severing element alined approximately with the perforations partially severing the sheets of the package, and a keeper for restraining the outer folds or sections of the package.
3. A package supporting fixture of the character described comprising supporting means including laterally located supporting members, the extremities of said supporting members being in-bent and constituting paper severing means, the supporting members being arranged to cause said in-bent extremities to be alined approximately with the perforations partially severing the sheets of the package, and a keeper engaged by said in-bent extremities of the supporting members for restraining the outer folds or sections of the package.
4. A package supporting fixture of the character described comprising supporting means including laterally located downwardly inclined supporting members, the extremities of said supporting members being in-bent and constituting paper severing means, the supporting members being arranged to cause said in-bent extremities to be alined approximately with the perforations partially severing the sheets of the package, a keeper engaged by said in-bent extremities of the supporting members for restraining the outer folds or sections of the package, and a gravity plate slidably supported on said supporting members.
5. A package supporting fixture of the character described comprising supporting means including laterally located resilient downwardly inclined supporting members, a paper severing element provided at the extremity of the supporting members, such paper severing element alined approximately with the perforations partially severing the sheets of the package, a keeper for restraining the outer folds or sections of the package, and a gravity plate slidably supported on said supporting members.
6. A package supporting fixture of the character described comprising supporting means including laterally located resilient downwardly inclined supporting members, the extremities of said supporting members being in-bent and constituting paper severing means, the supporting members being arranged to cause said in-bent extremities to be alined approximately with the perforations partially severing the sheets of the package, a keeper engaged by said in-bent extremities of the supporting members for restraining the outer folds or sections of the package.
7. A package supporting fixture of the character described comprising supporting means including laterally located downwardly inclined supporting members, the extremities of said supporting members being in-bent and constituting paper severing means, the supporting members being arranged to cause said in-bent extremities to be alined approximately with the perforations partially severing the sheets of the package, and a gravity plate slidably supported on said supporting members.
8. A package supporting fixture of the character described comprising supporting means including laterally located resilient downwardly inclined supporting members, a paper severing element provided at the extremity of the supporting members, such paper severing element alined approximately with the perforations partially severing the sheets of the package, and a keeper engaged by said in-bent extremities of the supporting members for restraining the outer folds or sections of the package.
9. A package supporting fixture of the character described comprising supporting means including laterally located resilient downwardly inclined supporting members, the extremities of said supporting members being in-bent and constituting paper severing means, the supporting members being arranged to cause said in-bent extremities to be alined approximately with the perforations partially severing the sheets of the package, and a keeper engaged by said in-bent extremities of the supporting members for restraining the outer folds or sections of the package.
